UNITED STATES PATENT OFFICE.

WALLACE G. IMHOFF, OF PITTSBURGH, PENNSYLVANIA, ASSIGNOR TO WARREN S. SMITH, OF NEW YORK, N. Y.

GALVANIZING FURNACE.

Application filed June 7, 1923. Serial No. 643,956.

To all whom it may concern:

Be it known that I, WALLACE G. IMHOFF, a citizen of the United States, residing at Pittsburgh, in the county of Allegheny and State of Pennsylvania, have invented a new and useful Improvement in a Galvanizing Furnace, of which the following is a specification.

This invention relates to a furnace for use in hot galvanizing.

Several difficulties are encountered in the fire-heating of galvanizing kettles to provide a bath suitable for hot galvanizing.

One difficulty has been local overheating of the kettle. This is of common occurrence, and is largely due to the arrangement necessarily employed for fire-heating a kettle in which the hot products of the combustion of coke, coal, oil, gas, or the like, are admitted to the galvanizing kettle by way of ports or flues in the refractory material of the setting adjacent to the lower portion of the kettle.

Another difficulty has been general overheating of the kettle. In using a galvanizing kettle from day to day it is kept continuously heated, but is used for less than half of each day. During the night, or at any time when the furnace is not under continuous observation, the fire may rise to an extent sufficient to produce overheating of the kettle.

It is a fact that when molten zinc is in contact with iron or other metal the molten zinc exercises a solvent action upon the metal with which it is in contact, forming a zinc alloy known as "dross." This action results in the more or less rapid destruction of the galvanizing kettle which contains the bath of molten zinc. It is also a known fact that overheating greatly accelerates the formation of dross and the destruction of the kettle, this action being particularly marked at temperatures above 900° Fahrenheit.

Another difficulty with the fire-heated galvanizing furnace commonly in use is that of maintaining a fine regulation of the temperature of the galvanizing bath during the actual galvanizing operations. The bath must be held at the most desirable temperature for the particular article being galvanized under the general operating con-

ditions, and the rate at which heat is abstracted from the bath.

One object of the present invention is to provide a galvanizing kettle in which the entire heating effect is distributed uniformly over the area of the galvanizing kettle to be heated, thus preventing any possibility of local overheating of any portion of the kettle.

Another object of the invention is to provide a galvanizing furnace in which the temperature to which the galvanizing kettle is raised may be set at a definite and unvarying point, thus preventing general overheating of the kettle.

A further object of the invention is to provide a galvanizing furnace in which the temperature of the kettle and the bath contained therein may be maintained under full and accurate control during the continuance of galvanizing operations.

These objects are attained by providing a galvanizing furnace in which the kettle is electrically heated, the electric heating means of the furnace being so arranged as to distribute the heating effect uniformly over the area of the kettle to be heated, and under such control that the temperature of the kettle and the bath therein may be set at a definite point, and may be maintained during the abstraction of heat from the bath in the kettle.

In the accompanying drawings Figure 1 is a vertical longitudinal section through a preferred form of the furnace of the present invention, such section being taken on the line 1—1 Figure 2; Figure 2 is a cross sectional view of the same form of furnace taken on the line 2—2 of Figure 1; Figure 3 is a wiring diagram showing all the resistance units of the circuit connected in straight series throughout; Figure 4 is a wiring diagram showing the resistance coils of the arrangement illustrated in Figures 1 and 2 connected in pairs, with the two units of each pair in parallel and the two pairs connected in two independent circuits; Figure 5 is a wiring diagram showing one resistance unit cut out of the circuit and the other resistance units connected in series; Figure 6 is a detail elevation of resistance units of modified form; Figure 7 is a section on line 7—7 Figure 6; Figure 8 is an

elevation of another modified form of unit; Figure 9 is a section on line 9—9 Figure 8; and Figure 10 is a cross sectional view through a form of the invention in which the kettle is heated by the inductive effect of an alternating electric current.

Referring to Figures 1 and 2 of the drawings, reference numeral 1 designates the furnace setting which is preferably composed of a good grade of fire brick. Within setting 1 is a continuous wall 2 of heat insulating brick; and within heat insulating wall 2 is the galvanizing kettle 3, which is commonly made of fire-box steel or other suitable metal.

The resistance units, which are designated generally by the reference numeral 4, comprise coils of wire made of some alloy such as nichrome which offers relatively great resistance to the passage of an electric current. These resistance units, or resistors, extend completely around the galvanizing kettle 3 and embrace it closely. For the sake of convenience, the resistors 4 are desirably imbedded in a cast 5 of a refractory cement, such as alundum cement or asbestos cement, which forms a casing for the kettle proper. The space between the cast 5 and the heat insulating wall 2 may be provided as shown, with a filling 6 of powdered magnesia, or the like, in order to provide perfect heat insulation for the kettle.

It should be noted that the number and spacing of the resistors 4 is such that their heating effect is distributed uniformly over the area of the kettle which they heat.

As shown in Figure 1, the uppermost unit A of the resistors connects with terminal wires *a* and *a'*, which form a circuit through the resistor. The next resistor B connects with terminal wires *b* and *b'*, the next resistor C with terminal wires *c* and *c'*, and the lowermost resistor D connects with terminal wires *d* and *d'*.

With reference to the wiring diagram shown in Figure 3 of the drawings, the line wires are designated by the reference numerals 8 and 9. In a shunt 10 of the line, and controlled by a switch 11 is a resistance 12. This resistance 12 may take any desired form, such as a resistance box, water rheostat, or any similar device. An ammeter 13 is also desirably provided in a shunt 14 having therein a switch 15.

As shown in this diagram, all the resistors A, B, C, and D of the circuit are connected in series. In such arrangement current passes by way of lead-in wire 8 and wire *a* to the resistor A, the double switch 16 and switch 17 being closed to complete the circuit. From resistor A the current passes by way of wire *a'*, the switch 18 being open, to the wire *b* leading to resistance B. From resistor B, the switches 19 and 20 being closed, the current passes

through wire *b'* to wire *c* leading to the resistor C. From resistor C, the switch 21 being open, the current passes by wires *c'* and *d* to the lowermost resistor D. From resistor D, switch 22 being closed, the current passes out to the line.

Figure 4 of the drawings shows a wiring diagram in which the resistors A and B are connected in parallel and the resistors C and D are connected in parallel, the two pairs thus forming two independent series parallel circuits. In this arrangement current flowing through the lead in line 8 flows by way of wires *a* and *b'* to both the resistors A and B, double throw switch 19 being thrown to interconnect these two wires. After passing through the resistors A and B the current flows into the return line 9 by way of switch 18, which is closed.

In this arrangement of the resistors the current is divided on the line, and a portion thereof flows through the auxiliary line wires 23 and 24 to the resistors C and D, which are also connected in parallel. In a shunt 25 of these auxiliary line wires is connected a resistance 26, this shunt being controlled by a switch 27. And in another shunt 28 of the wires is connected an ammeter 29, this shunt being controlled by a switch 30. From the lead in wire 23 of the line current flows by way of wires *c'* and *d*, switch 21 being closed, to the resistors C and D. From resistors C and D current flows by way of wires *c* and *d'* to the return wire 24 of the auxiliary line, switch 22 being closed, and thence back to the main line.

In the wiring diagram shown in Figure 5 of the drawings the connections are similar to those shown in Figure 3 thereof except that a double switch 31 is thrown to disconnect wires *c'* and *d* and to return current by way of an auxiliary return wire 32 to the main line. A switch 33 is also open so that wire *d'* is not connected with auxiliary return wire 32. In this arrangement the resistors A, B, and C are connected in series, and the resistor D is cut out completely from the circuit.

It will be understood that every element shown in each of the diagrams does not appear on each of the other diagrams. There may also be numerous other connections on the switchboard employed. Certain of the switches shown may further be utilized to cut additional resistors out of the circuit in the same manner shown and described for cutting the lowermost resistor D out of the circuit. It is obviously unnecessary that all such additions, modifications, and arrangements be shown as they obviously fall within the knowledge and capabilities of a skilled electrician, and the showing of the diagrams is illustrative merely of the manner in which the distribution and intensity

of the heating effect produced by the electric current may be regulated to secure the desired heating of the galvanizing kettle.

In conducting actual hot galvanizing operations, the temperature of the bath is preferably maintained at a temperature of from 820° Fahrenheit to 850° Fahrenheit. When the kettle is not in actual use but it is desired to maintain a bath which may be used instantly or rapidly raised to the desired temperature, the heating is preferably so regulated that the temperature of the bath is maintained at from 800° Fahrenheit to 820° Fahrenheit in order to secure convenience in conducting the galvanizing process with a minimum deterioration of the galvanizing kettle.

The greater variations in the temperature of the galvanizing kettle may be effected by the manner of connecting the resistors in the circuit, and the lesser variations by utilization of the line resistance unit or units, such as resistance boxes or rheostats.

If, therefore, the resistors are connected in series, as shown in the diagram of Figure 3, and it is desired to raise the temperature of the galvanizing kettle, the connections may be so changed as to parallel the resistors in pairs. Also, if so desired, all the resistors may be connected in parallel to further increase the heating effect of the circuit. If the heating effect is to be decreased from that produced when the resistors are all in series, the current may be further regulated by throwing the rheostat in the circuit. In leaving the kettle heated, but idle, the resistance coils of the circuit are arranged in the desired manner and the line resistance is so arranged that the temperature of the bath is maintained at the proper temperature.

If so desired, a thermostatic, or other automatic resistance of any well known type, may be interposed in the line to maintain the temperature of the kettle automatically at a certain point.

Instead of the coiled wire resistors 4, resistors of other types, as for example the hairpin form of nichrome resistor 34 shown in Figure 6 of the drawings or the carbon resistance blocks 34* shown in Figure 8 of the drawings, may be employed. When resistors of such other form are used, they may be connected in circuit in the same manner as the resistors 4 which have been described above.

With the form and arrangement of the furnace as described above, it is to be assumed that the line supplying electricity to the furnace carries a direct current. The form of the furnace shown in Figure 10 of the drawings is, however, designed for use with an alternating current. In the form of the device illustrated in Figure 10 the galvanizing kettle 35 is set in a furnace com-

prising an outer wall 36 of fire brick, and an inner wall 37 of heat insulating material immediately adjacent the kettle. Between outer wall 36 and inner wall 37 is a filling of cementitious material in which the current carrying coil 38 is imbedded. Layers or walls 39 of electrical insulating material are disposed on both sides of the coil 38 and the filling material in which it is imbedded. 70

The coil 38 itself is formed of a plurality 75 of turns of tubing composed of some material, such as copper, which is a good conductor of electricity. Each turn of the coil extends completely around the galvanizing kettle 35, and is kept cool by means of water 80 passing through the tubing of the coil. The heating effect in this modified form of the furnace is supplied by the induced currents produced by alternations of the current in coil 38. The coil itself is protected from 85 the heat by the inner heat insulating wall 37 and by the water flowing through the coil.

It will be understood that the heating effect of the current may be regulated by any 90 well known electrical means for such purpose, and that such regulation is a simple matter because the conducting means of the furnace comprise a single continuous coil.

Certain obvious advantages of the device 95 have been stated above, but other advantages incident to its fundamental idea and arrangement will readily be appreciated by those skilled in the art to which the invention pertains. It will also be understood 100 that the device is susceptible of numerous modifications over the form and arrangement illustrated and described herein, and the scope of the invention is therefore to be restricted only by the limitations contained 105 in the appended claims.

What I claim is:

1. In a furnace for hot galvanizing the combination of a metallic galvanizing kettle with an electric resistance circuit for 110 supplying heat thereto, means for regulating the current passing through such resistance circuit, and means for regulating the heating effect of the current supplied.

2. In a furnace for hot galvanizing the combination of a metallic galvanizing kettle with an electric resistance circuit comprising a plurality of resistors for supplying heat to said kettle, and means for connecting the several resistors of said circuit in series or in parallel for regulating the heating effect of the circuit. 115

3. In a furnace for hot galvanizing the combination of a galvanizing kettle with an electric resistance circuit comprising a plurality of resistors for supplying heat to said kettle, and means for cutting out resistors from the circuit and for connecting the resistors in series or in parallel to regulate the 120 heating effect of the circuit. 125

4. In a furnace for hot galvanizing the combination of a galvanizing kettle with an electric resistance circuit imbedded in cementitious material to form a casing embracing said kettle and comprising a plurality of resistors for supplying heat to said kettle, and means for connecting the resistors of said circuit in series or in parallel for regulating the heating effect of the circuit.
5. In a furnace for hot galvanizing the combination of a galvanizing kettle with a heat insulating setting therefor, and electrical means disposed between the setting and the kettle arranged to exert upon the latter a heating effect distributed uniformly over the area of the kettle to be heated.
6. In a furnace for hot galvanizing the combination of a galvanizing kettle with a heat insulating setting therefor, and electric resistors disposed between the setting and the kettle and arranged to exert a uniformly distributed heating effect over the area of the kettle to be heated.
7. In a furnace for hot galvanizing the combination of a galvanizing kettle with a heat insulating setting therefor, and an electric circuit disposed between the setting and the kettle and arranged to exert a uniformly distributed heating effect over the area of the kettle to be heated.
8. In a furnace for hot galvanizing the combination of a galvanizing kettle with a heat insulating setting therefor, and an electric resistance circuit disposed between the setting and the kettle and arranged to exert a uniformly distributed heating effect over the area of the kettle to be heated.
9. In a furnace for hot galvanizing the combination of a metallic galvanizing kettle with an electric resistance circuit comprising a plurality of resistors arranged to exert a uniformly distributed heating effect over the area of the kettle to be heated, and means for connecting the resistors in series or in parallel for regulating the heating effect of the circuit.
10. In a furnace for hot galvanizing the combination of a galvanizing kettle with an electric circuit imbedded in cementitious material to form a casing arranged to embrace the kettle for supplying heat thereto, said circuit being so arranged that the heating effect thereof is distributed uniformly over the area of the kettle to be heated.
11. In a furnace for hot galvanizing the combination of a galvanizing kettle with an electric resistance circuit comprising a plurality of resistors imbedded in cementitious material to form a casing arranged to embrace said kettle and supply heat thereto, said resistors being so arranged that the heating effect thereof is distributed uniformly over the area of the kettle to be heated.

In witness whereof, I hereunto set my hand.

WALLACE G. IMHOFF.
